(57) **CLAIM**

We claim the ornamental design for a handle on an article of luggage, as shown and described.

DESCRIPTION

FIG. 1 is a perspective view of a handle on an article of luggage.

FIG. 2 is a left side view of the handle of FIG. 1.

FIG. 3 is a right side view of the handle of FIG. 1.

FIG. 4 is a front or rear view of the handle of FIG. 1.

FIG. 5 is a front or rear view of the handle of FIG. 1.

FIG. 6 is a top view of the handle of FIG. 1; and,

FIG. 7 is a bottom view of the handle of FIG. 1.

The broken lines shown in the figures illustrate portions of a handle on an article of luggage and form no part of the claimed design.

1 Claim, 6 Drawing Sheets
